CLAIM

The ornamental design for a wearable display device, as shown and described.

DESCRIPTION

FIG. 1 is a front perspective view of a wearable display device according to a first embodiment of our design;

FIG. 2 is a front elevation view of the wearable display device of FIG. 1;

FIG. 3 is a back elevation view of the wearable display device of FIG. 1;

FIG. 4 is a right elevation view of the wearable display device of FIG. 1;

FIG. 5 is a left elevation view of the wearable display device of FIG. 1;

FIG. 6 is a top elevation view of the wearable display device of FIG. 1;

FIG. 7 is a bottom elevation view of the wearable display device of FIG. 1;

FIG. 8 is a front perspective view of a wearable display device according to a second embodiment of our design in a first configuration thereof;

FIG. 9 is a front elevation view of the wearable display device of FIG. 8;

FIG. 10 is a rear elevation view of the wearable display device of FIG. 8;

FIG. 11 is a right side elevation view of the wearable display device of FIG. 8;

FIG. 12 is a left side elevation view of the wearable display device of FIG. 8;

FIG. 13 is a top elevation view of the wearable display device of FIG. 8;

FIG. 14 is a bottom elevation view of the wearable display device of FIG. 8;

FIG. 15 is a front perspective view of the wearable display device according to the second embodiment of our design in a second configuration thereof;

FIG. 16 is a top elevation view of the wearable display device of FIG. 15;

FIG. 17 is a front perspective view of the wearable display device according to the second embodiment of our design in a third configuration thereof;

FIG. 18 is a top elevation view of the wearable display device of FIG. 17;

FIG. 19 is a rear perspective view of a wearable display device according to a third embodiment of our design;

FIG. 20A is a right elevation view of the wearable display device of FIG. 19 of which front, back, left, top, and bottom views are identical to the views shown in FIGS. 2, 3, and 5-7;

FIG. 20B is a detail view of the area indicated in FIG. 20A showing, in dotted phantom line, a feature that can be included along any portion of the surface on which it is shown;

FIG. 21 is a rear perspective view of a wearable display device according to a fourth embodiment of our design;

FIG. 22A is a right elevation view of the wearable display device of FIG. 21 of which front, back, left, top, and bottom views are identical to the views shown in FIGS. 2, 3, and 5-7; FIG. 22B is a detail view of the area indicated in FIG. 22A showing, in dotted phantom line, a feature that can be included along any portion of the surface on which it is shown;

FIG. 23 is a rear perspective view of a wearable display device according to a fifth embodiment of our design;

FIG. 24A is a right elevation view of the wearable display device of FIG. 23 of which front, back, left, top, and bottom views are identical to the views shown in FIGS. 2, 3, and 5-7; FIG. 24B is a detail view of the area indicated in FIG. 24A showing, in an un-outlined stipple-fill area, a feature that can be present as a light source visible through a translucent portion of the wearable display device;

FIG. 25 is a rear perspective view of a wearable display device according to a sixth embodiment of our design;

FIG. 26A is a right elevation view of the wearable display device of FIG. 25 of which front, back, left, top, and bottom views are identical to the views shown in FIGS. 2, 3, and 5-7;

FIG. 26B is a detail view of the area indicated in FIG. 26A showing, in an un-outlined stipple-fill area, a feature that can be present as a light source visible through a translucent portion of the wearable display device;

FIG. 27 is a front perspective view of a wearable display device according to a seventh embodiment of our design;

FIG. 28 is a front elevation view of the wearable display device of FIG. 27;

FIG. 29 is a left elevation view of the wearable display device of FIG. 27 of which back, right, top and bottom elevation views are identical to the views shown in FIGS. 3, 4, 6 and 7;

FIG. 30 is a front perspective view of a wearable display device according to an eighth embodiment of our design;

FIG. 31 is a front elevation view of the wearable display device of FIG. 30; and,

FIG. 32 is a left elevation view of the wearable display device of FIG. 30 of which back, right, top and bottom elevation views are identical to the views shown in FIGS. 3, 4, 6 and 7. Broken lines are environmental only and form no part of the claimed design.

Broken lines adjacent unshaded areas represent bounds of associated portions of the claimed design and form no part of the claimed design.
